UNITED STATES PATENT OFFICE.

BENJIMAN F. MYERS, OF TIFFIN, OHIO.

STOVE-DRUM.

SPECIFICATION forming part of Letters Patent No. 309,486, dated December 16, 1884.

Application filed March 4, 1884. (No model.)

To all whom it may concern:

Be it known that I, BENJIMAN F. MYERS, a citizen of the United States, residing at Tiffin, in the county of Seneca and State of Ohio, have invented certain new and useful Improvements in Stove-Drums, of which the following is a specification, reference being had therein to the accompanying drawings.

My invention relates to heaters to be used with stoves, which are so constructed as to be attachable or detachable, to suit the convenience and needs of the user.

My object is to provide a receptacle beneath an ordinary heating-stove, into and through which the heat emanating from the products of combustion may be passed at pleasure, for the purpose of heating the air of a room as near the floor as possible, as will be hereinafter more fully set forth.

In the accompanying drawings, making part of this specification, Figure 1 represents a perspective view of my invention connected to a stove; and Fig. 2 is a vertical section of a part of the two pipes which convey the products of combustion and change their course, as will be set forth. Fig. 3 is a perspective view of the drum detached.

In the figures, A represents an ordinary heating-stove, either for wood or coal, which rests upon a base, B, mounted upon suitable legs.

C represents a heat-receptacle, which is made of convenient size and shape, and located beneath the stove when in use. This receptacle is provided with a partition which runs from one end to a point near the other, as represented by d, Fig. 1, in dotted lines.

D and D' represent two pipes, which lead from the receptacle B, one passing up from one side and the other from the opposite side of the partition d. The upper ends of these pipes are provided with a hood, E, having an orifice which connects with the ordinary smoke-pipe of the stove. The hood E is centrally divided by a vertical partition, F, which has a laterally-extending top, f, to prevent the products from passing directly from one of the pipes, D, of the receptacle to the smoke-pipe.

a and e are elbows which connect the stove to the hood E.

n represents a damper operated by the rod e, and which is situated in the hood.

m is a door at one end of the receptacle and admits of its being cleaned of soot or ashes, and is provided with a register.

55

The operation of this appliance is as follows: When the fire is first made and a direct draft is desired, the damper n is turned down so that it closes the mouth of pipe D'. The products of combustion are then prevented from passing through the receptacle C. After the fire has been well started the damper is thrown up, so that it closes the passage of the products on one side of the partition F and causes them to descend through pipe D to the 65 receptacle O; thence they pass around the end of partition d, and thence up pipe D', directly to the smoke-pipe. Thus it will be seen that the heat from the products may be thrown into and passed through the receptacle close to the 70 floor, where the air is always coolest. When not needed, this contrivance is readily removed, and the ordinary smoke-pipe attached or connected to the elbow e.

I am aware that it is not new to provide a 75 stove with a base heating attachment consisting of a pipe leading downward from the smoke-escape of the stove and under the same, thence returning upward to the chimney, passing the smoke-escape, the said re- 80 turn-pipe being also provided with a smoke-connection and a damper.

My invention differs from the foregoing in providing a partitioned box to be placed under the stove and a partitioned hood connected 85 with the smoke-escape. The hood is provided with a damper, and the divisions thereof are independently connected to the respective divisions of the base. Further, the base is provided with a door containing a register, 90 for the purpose of cleaning and admitting a draft.

Having thus fully described my invention, what I claim as new, and desire to secure by Letters Patent, is—

95

1. A heating attachment for stoves, consisting of a shallow box which is partitioned into two communicating compartments, two upright pipes leading from the said compartments, and a partitioned hood on top the said pipes, the divisions of said hood having common connection to the smoke-escape of the stove, and one division only being provided with a damper and communicating with a

chimney, substantially as and for the purpose specified.

2. A heating attachment for stoves, consisting of a shallow box partitioned into two communicating compartments, and provided with a register and cleaning-door, two upright pipes leading from said compartments, and a partitioned hood on top said pipes, the divisions of said hood having common connection to the smoke-escape of the stove, and one division

only being provided with a damper and communicating with a chimney, substantially as and for the purpose specified.

In testimony whereof I affix my signature in presence of two witnesses.

BENJIMAN F. MYERS.
